WIRE-FORMING MACHINE

Harry M. Young, Webster Groves, Mo.

Application August 28, 1948, Serial No. 46,677

6 Claims. (Cl. 140—82)

1

This invention relates in general to forming machines and, more particularly, to wire-forming machines.

It is the primary object of the present invention to provide a wire-forming machine which is readily adaptable for producing a variety of pronged wire articles such as fence post clips, for example.

It is a further object of the present invention to provide a wire-forming machine which is reliable, efficient, and economical in operation, being high-speed, and requiring a minimum of manual labor.

It is a further object of the present invention to provide a wire-forming machine which is rugged and relatively simple in construction.

With the above and other objects in view, my invention resides in the novel features of form, construction, arrangement, and combination of parts presently described and pointed out in the claims.

In the accompanying drawing—

Figure 1 is a front elevational view of a wire-forming machine constructed in accordance with and embodying the present invention;

Figures 2, 3, 4, and 5 are fragmental sectional views taken along lines 2—2, 3—3, 4—4, and 5—5, respectively, of Figure 1;

Figure 6 is a fragmental sectional view taken along line 6—6 of Figure 2;

Figure 7 is an enlarged perspective view of a wire bending member forming a part of the present invention;

Figure 8 is a perspective view of the wire pipe hanger formed by the wire-forming machine of the present invention;

Figures 9, 10, 11, and 12 are fragmentary front views showing successive steps in the bending operation; and

Figures 13, 14, 15, and 16 are fragmentary transverse sectional views taken along lines 13—13, 14—14, 15—15, and 16—16 of Figures 9, 10, 11, and 12, respectively.

Referring now in more detail, and by reference characters to the drawing, which illustrates a preferred embodiment of the present invention, A designates a wire-forming machine comprising front and rear vertical plates B, B', secured together in spaced relation at their four corners by horizontal side rails C and bolts c. Also bolted upon the under faces of the lower side rails C, by means of bolts d, are leg members D.

An arm F, integral with, and in the same plane as, the plate B, extends laterally therefrom and supports, adjacent its outer end, a wire-straight-

2

ening mechanism G having a vertical set of rollers f, each roller thereof being suitably mounted on an adjustable slide block 2.

Mounted in spaced parallel relation on the outer face of the arm F, and forwardly of the mechanism G, are two vertical members 3, 3', having horizontally aligned feed apertures 4, 4', and supporting vertically spaced horizontal slide rods 5, 6. Slidably mounted upon, and extending vertically between, the rods 5, 6, is a feed carriage 7 provided with a downwardly presented wire guide shoulder 7' and having bolted upon its face two spaced guide clamps 8, 9, suitably adapted for loosely holding a wire a fed into the machine. A through the mechanism G beneath the guide shoulder 8. Pivotally mounted upon the feed carriage 7 by means of a pintle bolt 10 is a feed dog 11 provided at its lower end with a projecting handle 12, and being connected to one end of a spiral spring 13 which is, in turn, fastened at its outer end to the feed carriage 7. At its upper end, the feed dog 11 engages the underside of the wire a as it lies against the guide shoulder 8. Rearwardly of, and adjacent to, the vertical member 3 is a hold-back dog 14, pivoted on the arm F and biased by a tension spring 15 secured at its upper end to an arm 16 extending in vertically spaced parallel relation to the arm F from the plate B to which it is bolted at its forward end. The hold-back dog 14 is adapted for engagement with the wire a as it passes over a stationary guide block 17. The feed dog 11 and hold-back dog 14 are biased in such a manner that when the feed carriage 7 moves forwardly (i.e., to the left, reference being had to Figure 1), the feed dog 11 will tighten and grip the wire a so that it will be pulled forwardly with the carriage 7 and the hold-back dog 14 will correspondingly allow the wire a to move freely. Contrarywise, when the carriage 7 moves rearwardly, the feed dog 11 will release the wire a so that the carriage 7 can slide freely with respect thereto during such return movement, while the hold-back dog 14 will tend to grip the wire a and hold it stationary.

Bolted at its lower end to the arm F, and welded to the end of the arm 16, is a vertical support bar 18, and pivoted at its upper end thereon is a downwardly extending link 19 provided in its lower end with a slot 20 for operative driving connection to the feed carriage 7 by means of a stud 21.

Swingably secured to the link 19, approximately midway between its ends, is a pitman or connecting rod 22 pivotally secured at its forward

end by a crank pin 23 to an adjustable crank 24, more fully described in my co-pending application, Serial No. 735,207, filed March 17, 1947, now Patent No. 2,578,216, issued December 11, 1951. The adjustable crank is slidably mounted on a way block 25 formed integrally with an eccentric 26 which is, in turn, rigidly keyed upon the end of an auxiliary shaft 27 for rotation therewith. The adjustable crank 24 is integrally provided with a projecting boss 24' in which is 10 rotatably mounted an adjustment screw 28 threadedly engaged in a boss 25' formed integrally with the way block 25, whereby the amount of throw of the link 19 and the corresponding stroke of the feed carriage 7 may be adjusted as necessary for various desired lengths of wire *a*.

Operatively mounted at its upper end upon the eccentric 26 is an adjustable length pitman 29, connected at its lower end to the lower end of a vertically disposed slide 30 reciprocably mounted within the slideways 31, 31', associated with, and extending downwardly from, a guide block 32 adjustably mounted on the plate B for directing the wire *a* between the shearing member 33 formed on the upper end of the slide 30 and complementarily shaped shear block 34 rigidly secured to the block 32.

Mounted forwardly of the shear block 34 on the plate B is a forming assembly H comprising spaced parallel way-forming members 35 and a superposed forming plate 36, provided centrally with an elongated vertical slot 37 which, on the inner face of said plate 36, extends downwardly to connect with an inverted V-shaped forming slot 38 extending upwardly from the lower margin of the plate 36. Slidably disposed within the slot 37 is a stripping finger 39 having an arcuately shaped lower margin 40 which normally projects a short distance into the forming slot 38. An arm-like projection 41 extends outwardly from the upper portion of the stripping finger 39 through the slot 37 and beyond the outer face of the plate 36. Suitably secured to, and extending upwardly from, the upper face of the stripping finger 39 is a guide rod 42, the upper end of which projects through a circular aperture 43 provided in the upper face of the plate 36 and axially aligned with the slot 37. A coil spring 44 is encirclingly disposed about the member 42, abutting at its upper end against the upper side of the slot 37 for downwardly biasing the stripping finger 39.

Disposed within the way formed by the members 35 is a forming slide 45 provided in its lower portion with an outwardly projecting triangular boss 46 having an upper rounded apex, as at *b*. At its upper end, the forming slide 45 is attached by means of a stud 47 to the lower end of an adjustable link 48 which is, in turn, eccentrically connected at its upper end by means of a crank pin 49 to a rotary disk 50 keyed upon the projected end of a crank shaft 51 extending through the plates B, B', and journaled therein by suitable bearings 52, 53.

Pinned on that portion of the crank shaft 51 extending between the plates B, B', is a driving gear 54 for meshing engagement with a pinion 55 mounted upon an auxiliary shaft 27 whereby rotation of the crank shaft 51 will effect rotation of the auxiliary shaft 27. Keyed upon the crank shaft 51 is a disk or wheel 56 having secured thereon a cam-like projection 57 operatively engaging with the upper end of a slide bar 58 shiftably mounted within a guide block 59 secured to the inner face of the plate B'. The lower

end of the bar 58 is bifurcated in the provision of a clevis 60 for straddling engagement with a lever arm 61 extending therethrough and maintained against vertical displacement by a pin 62 extending between the lower portions of the clevis 60. The lever arm 61, at its inner end, is pivotally mounted on a suitable bracket 63 secured to the inner face of the plate B', and has mounted on its upwardly presented margin a loop 64 on which are attached the ends of spiral springs 65, 66, biasing the arm 61 upwardly, being secured at their upper ends to a bracket arm 67 suitably secured to the guide block 59. Outwardly of the spiral springs 65, 66, is a second pair of spiral springs 68, 69, secured at their upper ends to the bracket 63 and at their lower ends to opposite margins of an H-shaped wire bending member 70 extending through an enlarged aperture 71 in the plate B and pivotally mounted on the forming slide 45 by means of pins 72 extending through circular bosses 73 provided thereon. At its lower or forwardly projecting end, the wire bending member 70 is provided with leg portions 74, 74', lying in spaced parallel planes so to speak, but being at different angles to the main plane of the member 70, for purposes presently more fully appearing. Furthermore, the distance between the leg portions 74, 74', is equal to the transverse width of the forming slide 45 whereby, upon the member 70 being pivoted or rocked, the lower end of the legs 74 will swing outwardly within a plane perpendicular to the plane of the slide 45. The lower ends of the legs 74 are disposed angularly upward for reasons appearing more fully hereinafter. Extending across the upper end of said member 70, and secured at its ends within bosses 75 provided on the legs 74, 74', is a cross rod 76.

The crank shaft 51 is provided on its inwardly projecting end with a pulley 77 having a belt 78 thereon which is operatively connected to a conventional electric motor (not shown).

An adjustable stop means 79 is provided forwardly of the forming assembly H whereby the length of the wire *a* cut by the shearing member 33 may be adjusted.

Secured at its forward end to the face of the plate B below the stop means 79 is a horizontally extending stripping bar 80 which is formed so that its free end is spaced outwardly from the slide 45.

In operation, the slide 45 is moved upwardly responsive to rotation of the disk 50, whereby the sheared length of wire *a* is carried upwardly by the triangular boss 46 and driven into the forming slot 38, and is shaped in conformity with the shape of the boss 46. Simultaneously therewith, the stripping finger 39 is driven upwardly within the slot 37 and out of the forming slot 38, thereby compressing the spring 44. As the forming boss 46 is carried downwardly through further rotation of the disk 50, subsequent to the forming action, the spring 44, being thereby released, drives the stripping finger 39 downwardly to eject from the forming slot 38 any formed wire sections which, through friction, might have remained therein after the withdrawal of the forming boss 46. The abutment of the under face of the projection 41 upon the lower side of the aperture or slot 37 on the outer face of the plate 36 limits the downward movement of the stripping finger 39 so that only a defined portion thereof projects into the slot 37 in stripping action. As the forming slide 45 reaches the upper limit of its stroke, and the adjustable link 48

passes through its top dead center position, the cam projection 57 of the wheel 56 passes through the lowermost arc of its travel and engages the upper end of the slide bar 58, driving it sharply downwardly, and correspondingly rocking the lever arm 61 downwardly into contact with the cross rod 78 of the member 70, whereupon the upper portion of said member 78 is pivoted downwardly, thus causing the lower leg portions to be swung upwardly and outwardly into bending contact with the end portions of the wire *a* and thereby bending the lower portion thereof outwardly to form a completed fence post clip *M* having prongs *p*, *p'*, which lie in parallel planes, so to speak, but are non-parallel to each other. The wire *a*, when formed, is carried downwardly by the boss 46 as the forming slide 45 travels downwardly. In such travel, one of the bent end portions of the wire *a* is brought into contact with the upper margin of the stripping bar 80. By such impact, the wire *a* is tripped forwardly, whereupon it falls outwardly from the machine A and into a suitable receptacle (not shown).

It should be understood that changes and modifications in the form, construction, arrangement, and combination of the several parts of the wire-forming machine may be made and substituted for those herein shown and described without departing from the nature and principle of my invention.

Having thus described my invention, what I claim and desire to secure by Letters Patent is:

1. A machine for forming a piece of wire into a predetermined shape, which machine includes a frame, intermittent wire-feeding means operatively mounted on the frame for feeding the wire along a substantially straight path, cut-off means operatively mounted on the frame along said path and being adapted to cut off the wire into pieces of predetermined length, a stationary die mounted on the frame on one side of said path and having a recess of predetermined shape opening toward the path along which the wire moves when it is being intermittently fed by the feeding means, a sliding die reciprocably mounted on the frame and being initially positioned on the opposite side of said path with respect to the stationary die, said sliding die having a member adapted for movement across said path into the recess of the stationary die and being adapted to engage and force the central portion of the cut-off section of wire into said recess for bending it into conformity to the shape thereof, die reciprocating means operatively associated with the sliding die for shifting the die from initial position into wire-forming engagement within the stationary die and thereafter returning the sliding die to initial position, means pivotally mounted on the slide and being swingable about an axis transverse to the line of movement of the sliding die after the sliding die reaches the upper limit of its stroke and thereby bending the end portions of the wire out of the plane in which originally bent, and driving means operatively connected to the feeding means, cut-off means and die reciprocating means for operating the feeding means, cut-off means and sliding die in timed relation to each other.

2. A machine for forming a piece of wire into a predetermined shape, which machine includes a frame, intermittent wire-feeding means operatively mounted on the frame for feeding the wire along a substantially straight path, cut-off means operatively mounted on the frame along said path and being adapted to cut off the wire into

pieces of predetermined length, a stationary die mounted on the frame on one side of said path and having a recess of predetermined shape opening toward the path along which the wire moves when it is being intermittently fed by the feeding means, a sliding die reciprocably mounted on the frame and being initially positioned on the opposite side of said path with respect to the stationary die, said sliding die having a member adapted for movement across said path into the recess of the stationary die and being adapted to engage and force the central portion of the cut-off section of wire into said recess for bending it into conformity to the shape thereof, die reciprocating means operatively associated with the sliding die for shifting the die from initial position into wire-forming engagement within the stationary die and thereafter returning the sliding die to initial position, means pivotally mounted on the slide and being swingable about an axis transverse to the line of movement of the sliding die after the sliding die reaches the upper limit of its stroke and thereby bending the end portions of the wire out of the plane in which originally bent, stripper means operatively mounted in the stationary die for ejecting the formed piece of wire as the sliding die returns to initial position, and driving means operatively connected to the feeding means, cut-off means and die reciprocating means for operating the feeding means, cut-off means and sliding die in timed relation to each other.

3. A machine for forming a piece of wire into a predetermined shape, which machine includes a frame, intermittent wire-feeding means operatively mounted on the frame for feeding the wire along a substantially straight path, cut-off means operatively mounted on the frame along said path between the stationary die and the intermittent feeding means and being adapted to cut off a section of the wire, stop means mounted on the frame on the opposite side of the stationary die with respect to the cut-off means, said stop means having an abutment face extending across the path along which the wire moves when it is being fed by the intermittent feeding means, said abutment face being adapted to contact the oncoming end of the wire as it is fed so that the piece of wire severed by the cut-off means in each successive cycle of operation of the machine will be determined by the distance between said face and the cut-off means so that the successively severed pieces of wire will be of the same predetermined length, a stationary die mounted on the frame on one side of said path and having a recess of predetermined shape opening toward the path along which the wire moves when it is being intermittently fed by the feeding means, a sliding die reciprocably mounted on the frame and being initially positioned on the opposite side of said path with respect to the stationary die, said sliding die having a member adapted for movement across said path into the recess of the stationary die and being adapted to engage and force the central portion of the cut-off section of wire into said recess for bending it into conformity to the shape thereof, die reciprocating means operatively associated with the sliding die for shifting the die from initial position into wire-forming engagement within the stationary die and thereafter returning the sliding die to initial position, means pivotally mounted on the slide and being swingable about an axis transverse to the line of movement of the sliding die after the sliding die reaches the upper limit of its stroke and there-

by bending the end portions of the wire out of the plane in which originally bent, and driving means operatively connected to the feeding means, cut-off means and die reciprocating means for operating the feeding means, cut-off means and sliding die in timed relation to each other.

4. A machine for forming a piece of wire into a predetermined shape, which machine includes a frame, intermittent wire-feeding means operatively mounted on the frame for feeding the wire along a substantially straight path, cut-off means operatively mounted on the frame along said path between the stationary die and the intermittent feeding means and being adapted to cut off a section of the wire, stop means adjustably mounted on the frame on the opposite side of the stationary die with respect to the cut-off means, said stop means having an abutment face extending across the path along which the wire moves when it is being fed by the intermittent feeding means, said abutment face being adapted to contact the oncoming end of the wire as it is fed so that the piece of wire severed by the cut-off means in each successive cycle of operation of the machine will be determined by the distance between said face and the cut-off means so that the successively severed pieces of wire will be of the same predetermined length as established by the particular adjustment of the stop means, a stationary die mounted on the frame on one side of said path and having a recess of predetermined shape opening toward the path along which the wire moves when it is being intermittently fed by the feeding means, a sliding die reciprocably mounted on the frame and being initially positioned on the opposite side of said path with respect to the stationary die, said sliding die having a member adapted for movement across said path into the recess of the stationary die and being adapted to engage and force the central portion of the cut-off section of wire into said recess for bending it into conformity to the shape thereof, die reciprocating means operatively associated with the sliding die for shifting the die from initial position into wire-forming engagement within the stationary die and thereafter returning the sliding die to initial position, means pivotally mounted on the slide and being swingable about an axis transverse to the line of movement of the sliding die after the sliding die reaches the upper limit of its stroke and thereby bending the end portions of the wire out of the plane in which originally bent, and driving means operatively connected to the feeding means, cut-off means and die reciprocating means for operating the feeding means, cut-off means and sliding die in timed relation to each other:

5. A machine for forming a piece of wire into a predetermined shape, which machine includes a frame, intermittent wire-feeding means operatively mounted on the frame for feeding the wire along a substantially straight path, cut-off means operatively mounted on the frame along said path and being adapted to cut off the wire into pieces of predetermined length, a stationary die mounted on the frame on one side of said path and having a recess of predetermined shape opening toward the path along which the wire moves when it is being intermittently fed by the feeding means, a sliding die reciprocably mounted on the frame and being initially positioned on the opposite side of said path with respect to the stationary die, said sliding die having a member adapted for movement across said path

into the recess of the stationary die and being adapted to engage and force the central portion of the cut-off section of wire into said recess for bending it into conformity to the shape thereof, die reciprocating means operatively associated with the sliding die for shifting the die from initial position into wire-forming engagement within the stationary die and thereafter returning the sliding die to initial position, an H-shaped bender pivotally mounted on the slide and being swingable about an axis transverse to the line of movement of the sliding die after the sliding die reaches the upper limit of its stroke and thereby bending the end portions of the wire out of the plane in which originally bent, and driving means operatively connected to the feeding means, cut-off means and die reciprocating means for operating the feeding means, cut-off means and sliding die in timed relation to each other.

6. A machine for forming a piece of wire into a predetermined shape, which machine includes a frame, intermittent wire-feeding means operatively mounted on the frame for feeding the wire along a substantially straight path, cut-off means operatively mounted on the frame along said path and being adapted to cut off the wire into pieces of predetermined length, a stationary die mounted on the frame on one side of said path and having a recess of predetermined shape opening toward the path along which the wire moves when it is being intermittently fed by the feeding means, a sliding die reciprocably mounted on the frame and being initially positioned on the opposite side of said path with respect to the stationary die, said sliding die having a member adapted for movement across said path into the recess of the stationary die and being adapted to engage and force the central portion of the cut-off section of wire into said recess for bending it into conformity to the shape thereof, die reciprocating means operatively associated with the sliding die for shifting the die from initial position into wire-forming engagement within the stationary die and thereafter returning the sliding die to initial position, a bender swingably mounted on the slide for rocking movement about an axis substantially parallel to and spaced from the path of movement of the wire and being provided with outwardly swinging wire-engaging means for bending the end portions of the wire out of the plane in which originally bent, and driving means operatively connected to the feeding means, cut-off means and die reciprocating means for operating the feeding means, cut-off means and sliding die in timed relation to each other.
